UNITED STATES PATENT OFFICE.

AUSTIN B. HAYDEN, OF CHICAGO, ILLINOIS, ASSIGNOR TO COMPUTING SCALE COMPANY OF AMERICA, A CORPORATION OF NEW JERSEY.

COMPUTING-SCALE.

SPECIFICATION forming part of Letters Patent No. 770,804, dated September 27, 1904.

Application filed January 18, 1902. Serial No. 90,234. (No model.)

To all whom it may concern:

Be it known that I, AUSTIN B. HAYDEN, a citizen of the United States, residing at Chicago, in the county of Cook and State of Illinois, have invented a new and useful Improvement in Computing-Scales, of which the following is a specification.

My invention relates particularly to computing-scales of the spring-balance type—such, for instance, as that described in my pending application, Serial No. 54,667, filed April 6, 1901.

My primary object is to provide a scale of this type of generally-improved construction, particular attention having been paid to securing simplicity of construction, ease of adjustment, accuracy of operation, and freedom from violent oscillation.

The invention is illustrated in its preferred embodiment in the accompanying drawings, in which—

Figure 1 represents a front elevational view of a spring-balance computing-scale, a portion of the outer casing being broken away; Fig. 2, a vertical sectional view taken as indicated at line 2 of Fig. 3; Fig. 3, a horizontal section taken as indicated at line 3 of Fig. 2; Fig. 4, a broken horizontal section taken as indicated at line 4 of Fig. 2; and Figs. 5 and 6, vertical and horizontal detail sectional views illustrating the adjustment of a reference-pointer employed at the rear side of the scale, Fig. 6 being a section taken as indicated at line 6 of Fig. 5.

A represents a non-rotatable casing constituting, in effect, a portion of a frame, said casing being supported by a member A', connected with a standard A², and the latter is adapted to be mounted on a counter or base, as usual. The connection between the standard A² and the member A' is formed by a hanger such as is usually employed for pendent scales. Thus an eye is formed in the part A' and a pin or bolt passing loosely through the eye connects the two arms of a clip A⁹, surrounding the standard A₂.

The letter B indicates a combined weight and value indicating cylinder fixed at its upper end to a spiral-equipped cylinder-rotat-

ing rod B', supported from a ball-bearing B²; A³, an internal standard supported from a cross-head A⁴, connected with a bolt A⁵, fixedly secured to the bottom A⁶ of the casing A; C, a spring-supported load-actuated member or load-hanger; C', a U-shaped load-pan support connected with the member C; C², a load-pan of usual form suspended from the member C', and C³ a rod-actuating member yieldingly connected with the member C.

The casing A comprises a cylindrical body a, preferably of sheet metal, and having front and rear sight-glasses a¹ a², respectively, a spider a³, bearing an upturned ball-cup a⁴, a top a⁵, fitting over the spider a³, the bottom A⁶ comprising members a⁶ a⁷ a⁸ and rods a⁹, connecting the member a⁷ with the spider a³ and provided with eyes a¹⁰, connected by cotter-pins a¹¹ with perforated lugs a¹², with which the member A' is provided. The members a⁶ and a⁷ are preferably heavy to give rigidity and strength to the casing as well as to bring the center of gravity low, while the member a⁸ is a thin covering conforming to the casing. The casing A is provided at its front side with a price-index a¹³, located on the casing beside the sight-opening and giving the prices per unit of weight, as indicated by the vertical row of numerals in Fig. 1. The casing is further provided with a plate a¹⁴, crossing the sight-opening a¹ and behind which a reversely-arranged set of weight indications on the cylinder may be concealed, said indications being thus brought into position to be exposed through the rear sight-opening, as will be readily understood. The sight-glass a¹ is provided with a vertical reference-line a¹⁵. The sight-glass a² at the rear side of the casing is a short glass which serves to permit the weight-indicating characters of the inner revolute cylinder to be exposed to the view of the customer. There is provided thereat an adjustable reference-point a¹⁶, carried by nut a¹⁷, working on a horizontally-disposed threaded rod a¹⁸, supported from the casing. The construction is such that when the rod a¹⁸ is turned the nut moves transversely in one direction or the other, according to the direction in which the rod is turned.

The standard A³ comprises two vertical rods a¹⁹, projecting upwardly from the cross-head A⁴ through suitable openings in the lower end of the casing A, and a top cross member a²⁰. The member a²⁰ supports springs a²¹, which are connected therewith in any usual manner and from which the member C is suspended. The cross-head A⁴ has a central vertical perforation a²², which receives loosely the threaded 10 stud or bolt A⁵, and said cross-head has a horizontal slot a²³, which receives a nut a²⁴, which screws on the bolt A⁵. A spring a²⁵, confined between said nut and the lower wall of the slot a²³, serves to force the cross-head 15 A⁴ downwardly and keep the upper wall of the slot a²³ in close contact with the upper surface of the nut a²⁴. Slots or perforations a²⁶ a²⁷ in the cross-head A⁴ and the lower cylinder end A⁶ receive the vertical members of the load-20 pan supports C'. A cap a²⁸ screws onto the ball-cup a⁴ and serves to inclose said ball-cup and hold the cover a⁵ in place.

The inner cylinder B comprises, preferably, a light sheet-metal cylindrical body b, provided at its lower end with an inturned flange or strengthening-rib b¹ and provided at its upper end with a spider b², having a central hub which receives and is firmly fixed to the upper end of the rod B'. The upper end of 25 the rod B' is reduced in cross-section and passes freely through the cup a⁴ and is equipped at its upper extremity with a cone b³ and lock-nut b⁴. The lower end of the rod B' has a socket b⁵, which receives a pin b⁶, projecting upwardly from the head of the bolt A⁵. It will be seen that the construction permits 30 the rod B' to be adjusted vertically at the ball-bearing, so that the cylinder B may have its rows of value-indicating characters brought 35 into horizontal alinement with their respective price-index characters of the outer casing. The cylinder B is provided circumferentially with horizontal rows b⁷ of value-indicating characters and with a horizontal row 40 b⁸ of weight-indicating characters, the row b⁸ being located immediately below the plate a¹⁴. In Fig. 1 a portion of the outer casing has 45 been broken away to expose a portion of the value-indicating cylinder beyond the sight-opening. It will be understood that when the 50 load-pan is depressed the cylinder B will be caused to rotate in the direction indicated by the arrow in Fig. 1.

The member C carries at one end a roller c, 55 which engages the adjacent rod a¹⁹, and at the other end a roller c', which engages the adjacent rod a¹⁹ and is journaled in a spring-projected yoke c². The yoke c² may be of any desired form; but that shown has a stem seating in a socket in the member C, and a spring confined in the socket behind the stem serves to project the yoke. Said member C carries upwardly-projecting studs or pins c³ c⁴, with the latter of which is connected, preferably by 60 65 a head or nut, the laterally-projecting end of

a plunger-stem c⁵, working in a cylinder c⁶, the cylinder c⁶ being carried by the rod-actuating member C³. The member C³ is guided by the rods c³ c⁴ and is provided with a roller c⁷, which engages a spiral c⁸, with which the rod B' is provided, the spiral being held up against the roller by its end bearings or by contact with the rear wall of the slot, which rear wall may for convenience be formed by a cross-pin, as shown in section in Fig. 1. The plunger c⁵ 70 is provided with a perforated disk c⁹ and a valve-disk c¹⁰, carried thereby and having its movement on the stem c⁵ limited by a pin c¹¹. When the member C is violently depressed by a load thrown upon the pan C', the plunger 75 works comparatively idly in its cylinder and the member C separates from the member C³. In operation the member C settles down comparatively slowly and actuates the computing-cylinder. As it settles down it meets the member C, returning under the reaction of its 80 springs, and the valve c¹⁰ then acts to oppose the upward movement of the member C, so that a state of equilibrium is quickly produced. The dash-pot and its piston thus act 85 as a governor to control the relative movements of the hanger and actuator.

The member C is provided with knife-edges c¹² in vertical alinement with the shaft of the roller c⁷, said knife-edges affording bearings 90 for the member C³. These knife-edges serve to limit the downward movement of the member C³, and a spring c¹³, surrounding the guide c⁴ below the laterally-projecting end of the rod c⁶ serves to limit the upward movement 95 of said member, the plunger c⁵ never coming in contact with the ends of its cylinder. If desired, oil may be employed in the cylinder c⁶.

It is evident that the position of the cylinder B with reference to the index-line a¹⁵ will 100 be determined by the height of the roller c⁷, and it follows that by adjusting the height of the standard A³ by means of the nut a²⁴ the indicating-cylinder may be turned on its axis to bring its vertically-disposed zero-line into 105 alinement with the reference-line a¹⁵.

The manner of adjustment and operation may be briefly summarized as follows: The shaft B' may be raised or lowered by adjustment of the cone b³ and nut b⁴, thereby bringing the value-indicating rows of the cylinder into proper alinement with the corresponding characters of the price-index. The height of the spring-supporting standard A³ may be adjusted by means of the nut a²⁴, thereby bringing the zero-line of the computing-cylinder into alinement with the reference-line a¹⁵ of the casing A. When an article to be weighed is thrown upon the load-pan C', it serves to violently depress the member C, while the member C³ is retarded by inertia and friction. The member C³ then settles down under its own weight and actuates the computing-cylinder without any shock to the parts. As it settles down it meets the member C, moving 110 115 120 125 130

upwardly under the reaction of its springs. The valve c^{10} operates to permit the member C to separate quite freely from the member C^3 , but opposes the upward movement of the member C with reference to the member C^3 .

It will be observed that the cylinder is suspended from its supporting-bearing, or, in other words, its supporting-bearing is located above its center of gravity, the pin b^6 serving simply to prevent lateral deflection of the cylinder and its axial shaft, and it is obvious that the beneficial results of such an arrangement of the parts will be secured even though the bearing were not located as high as shown above the center of gravity, although the arrangement shown is preferred.

It is clear that many of the features of improvement described may be applied to other scales than the particular form herein shown. Hence no undue limitation is to be understood from the foregoing detailed description.

What I claim as new, and desire to secure by Letters Patent, is—

1. In a spring-balance scale, the combination with the vertically-arranged rotary indicating-cylinder, an axial rod to which the cylinder is connected and a bearing in which said rod is journaled and from which it is suspended, located above the upper end of the cylinder, of a spring-suspended load-hanger located within the cylinder below the bearing and connections between the hanger and rod, whereby the cylinder is rotated in accordance with the movements of the hanger; substantially as described.

2. In a spring-balance scale, the combination with the vertically-arranged rotary indicating-cylinder and a bearing in which it is journaled and from which it is suspended, located above the cylinder, of a spring-supporting frame projecting into said cylinder from the lower end, springs suspended from said frame, a load-hanger supported by the springs and connections between said hanger and cylinder whereby the latter is rotated in accordance with the movement of the former; substantially as described.

3. In a spring-balance scale, the combination with the graduated indicating-cylinder, main frame in which it is journaled, a load-hanger and connections whereby the cylinder is rotated in accordance with the movements of the hanger, of a spring-supporting frame projecting below the main frame, adjusting mechanism located below the main frame and connecting the main and spring frames and springs suspended from the upper end of the spring-frame and supporting the load-hanger; substantially as described.

4. In a spring-balance scale, the combination with the graduated indicating-cylinder mounted on a vertical axis, a main frame having a cylinder-supporting bearing located above the center of gravity of the cylinder, a load-hanger and connections whereby the cylinder is ro-

tated in accordance with the movements of the hanger, of a spring-supporting frame adjustably mounted on the main frame below the cylinder and projecting into the lower end of the cylinder, springs suspended from the upper end of the spring-frame and connected with the load-hanger; substantially as described.

5. In a spring-balance scale, the combination with the indicator and the spring-suspended load-hanger, of an indicator-actuator supported on the load-hanger but free to move independently thereof, connections whereby the actuator imparts movement to the indicator corresponding to the movements of the load-hanger and a governor interposed between the actuator and load-hanger and controlling the relative ratio of movement of the hanger and actuator; substantially as described.

6. In a spring-balance scale, the combination with the indicator and the spring-suspended load-hanger, of an indicator-actuator supported on the load-hanger but free to move independently thereof, connections whereby the actuator imparts movements to the indicator corresponding to the movements of the load-hanger and a dash-pot and piston, connected the one with the hanger and the other with the actuator whereby the relative movement of said parts is controlled; substantially as described.

7. In a spring-balance scale, the combination with the indicator and the spring-suspended load-hanger, of an indicator-actuator, guides for the actuator mounted on the hanger, whereby said actuator is supported on but is free to move independently of the hanger, connections whereby the actuator imparts movements to the indicator corresponding to the movements of the hanger, and a dash-pot and piston working therein, one connected with the actuator and the other with one of the actuator-guides; substantially as described.

8. In a computing-scale, the combination of a rotary computing-cylinder with a vertical axis, a spiral-equipped cylinder-actuating rod connected with said cylinder, a yieldingly-supported load-hanger, and a rod-actuating member yieldingly connected with said load-hanger and vertically reciprocable with relation thereto.

9. In a scale of the character described, the combination of a computing-cylinder, a spiral-equipped vertical shaft fixed to rotate with said cylinder, a spring-supporting standard, a spring connected therewith, a load-actuated member connected with said spring, a rod-actuating member surmounting said load-actuated member and provided with spiral-engaging means, and cylinder and plunger connection between said rod-actuating member and said load-actuating member, for the purpose set forth.

10. In a scale of the character described, the

combination of an outer casing, an inner vertically - arranged rotary cylinder, a spiral-equipped shaft fixed to rotate with said cylinder, a stud projecting upwardly from the 5 upper end of said cylinder, an antifriction-bearing between said stud and the upper end of said casing, said cylinder being vertically adjustable through the medium of said bearing, means for holding the lower end of the 10 cylinder-shaft in position, a spring-supported load-actuated member, and rod - actuating means connected with said load - actuated member.

11. In a scale of the character described, the 15 combination of an outer casing provided with a vertical price-index, a computing-cylinder provided with horizontal value - indicating rows, a spiral-equipped rod serving to actuate said cylinder, a load-hanger, connections 20 between the hanger and rod whereby the rod is rotated by the movement of the hanger, springs supporting said load-hanger, and a standard supporting said springs, and comprising rods located on opposite sides of said 25 cylinder - shaft, a cross-head connecting the lower ends of said rods, and screw connection between the lower end of said casing and said cross-head whereby said standard-rods may be simultaneously adjusted, for the purpose set 30 forth.

12. In a scale of the character described, the combination of an outer casing provided with

a vertical price-index, a computing-cylinder provided with horizontal value - indicating rows, a spiral-equipped rod serving to actuate said cylinder, a load-hanger, connections between the hanger and rod whereby the rod is rotated by the movement of the hanger, springs supporting said load-hanger, and a standard supporting said springs, and comprising rods located on opposite sides of said cylinder - shaft, a cross-head connecting the lower ends of said rods, a central fixed screw connected with the lower end of said casing, and a nut on said screw working in the slot 45 in said cross-head, whereby vertical adjustment of said standard-rods is effected, for the purpose set forth.

13. In a spring-balance scale the combination with a vertically - arranged cylindrical 50 casing, a bottom for said casing, a frame carried by said bottom and projecting up into the casing, an indicator, counterbalance-springs suspended from the frame, a load-support projecting through the bottom and means whereby the movements of the load-support operate the indicator, of rods outside of the casing, and attached at their lower ends to the bottom and a suspension device connected with the upper ends of the rods.

AUSTIN B. HAYDEN.
